UNITED STATES PATENT OFFICE

118,638

DESIGN FOR A PORTABLE FOOD DISPENSER STAND

George L. Ely, New York, N. Y.

Application October 25, 1939, Serial No. 87,841

Term of patent 14 years

To all whom it may concern:

Be it known that I, George L. Ely, a citizen of the United States, residing in the Borough of Manhattan, city, county, and State of New York, have invented a new, original, and ornamental Design for a Portable Food Dispenser Stand, of which the following is a specification, reference being had to the accompanying drawing, forming part thereof.

I claim:

The ornamental design for a portable food dispenser stand, as shown.

GEORGE L. ELY.
